UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

TYPEWRITING MACHINE.

Application filed October 20, 1922. Serial No. 669,668.

To all whom it may concern:

Be it known that I, JESSE A. B. SMITH, a citizen of the United States, residing in Stamford, in the county of Fairfield and 5 State of Connecticut, have invented certain new and useful Improvements in Typewriting Machines, of which the following is a specification.

This invention relates to typewriters having letter-feeding platen-carriages, and more particularly to the mechanism which controls the side margins on the work-sheets.

In making out bills, bookkeeping accounts, and other forms, the first entry is typed close 15 to the left-hand edge of the work-sheet. Following this, items are generally listed in a column which is indented some distance to the right of said first entry.

The typing of these items has usually required the return of the carriage to the right-hand margin-stop that was set for the first entry. This stop located the work-sheet some distance to the left of the desired starting point, making it necessary to tabulate 25 from this point to the desired position.

A feature of the present invention is the automatic restoration of the margin-stop to re-locate the carriage in the right-hand or lower position on the letter-feeding scale, for 30 the first entry of each succeeding bill or form. The usual feed-roll release-lever, which the typist depresses to remove the finished work-sheet, is connected to cause disengagement of the right-hand margin- 35 stop from its fixed adjustable position. Accordingly, on the succeeding return movement of the carriage with the feed-roll release-lever depressed, the margin-stop will be carried back therewith to its right-hand 40 or lower scale-position, to register the carriage in position for typing the first entry. When the feed-roll release-lever is returned to its normal position, the margin-stop will return to normal position and again lock 45 itself against movement to the right. After the first entry has been made, the typist may slide the margin-stop against a fixed collar on the margin-stop-rod in the usual manner, so that the succeeding return movements of 50 the carriage are arrested in the item position.

Preferably, however, a spring is provided which will automatically return the margin-stop to the fixed collar as the carriage is advanced to the left during the typing of the 55 first entry. The margin-stop pawl usually

engages a type of rack-rod, which allows the margin-stop pawl to clip over the teeth on the rack when the stop is pushed or pulled to the left toward a higher scale-position.

Other features and advantages will hereinafter appear.

In the accompanying drawings,

Figure 1 is a top plan view showing a portion of an Underwood typewriter with the invention attached thereto.

Figure 2 is an end view, partly in section, showing the feed-roll mechanism in normal operating position, which is non-effective in releasing the right-hand margin-stop.

Figure 3 is a portion of an end view, partly in section, similar to Figure 2, showing the feed-roll release mechanism positioned to throw the feed-rolls off the platen, and which at the same time disengages the right-hand margin-release stop-pawl preparatory to shifting the same to a lower scale-position.

Figure 4 is a fragment of a top view, showing the margin-stop pawl displaced from the rack-rod.

Figure 5 is a perspective view of the feed-roll release-lever bearing-shaft, and connections for the links to the feed-rolls and the right-hand margin-stop release, shown with the parts separated.

Referring to the drawings, a platen-carriage, designated as a whole as 10, is of the well-known oscillating type found on the Underwood typewriter. It has journaled thereon a platen-axle 11 on which is mounted a revoluble platen 12. The usual feed-roll-releasing mechanism 13 co-operates with the platen 12 to hold a work-sheet 12^a against the platen 12. The feed-roll-releasing mechanism 13 comprises a stationary supporting-rod 14 supported below the platen 12. Arms 15, extending in opposite directions and carrying on their ends rods 16, are pivotally mounted on rod 14. Paper feed-rolls 17 are mounted on the rods 16. The arms 15 are engaged by springs 18 which have a tendency to throw the rolls 17 against the platen 12, or the work-piece 12^a thereon.

The arms 15 are also provided with projections or tappets 19 arranged to embrace a rock-shaft 20. The shaft 20 is suitably mounted (not shown) to swing about the supporting-rod 14, and is provided with a flattened or cam portion 21 arranged to en-

2
gage tappets 19. Thus when the shaft 20 is turned by a crank-arm 22, the tappets 19 will be spread apart and feed-rolls 17 will be thrown off the platen 12 to release the 5 work sheet 12^a. The free end of the crank-arm 22 is connected to the lower end of an upwardly-extending link 23, the upper end of which is pivotally connected at 24 to a crank-arm 25. A short rock-shaft 26 rigidly 10 supports crank-arm 25 and is journaled between a bracket 27 (projecting from the sides of the frame of carriage 10) and the frame of carriage 10, see Figures 1 and 5. The outer end of the shaft 26 has a feed-roll 15 release or control lever 28 fastened thereto to operate the feed-roll-releasing mechanism 13 in the usual manner. So far as above described, the structure is similar or equivalent to the well-known feed-roll-releasing mechanism 20 now in general use on typewriters.

My improvement consists in providing means operated simultaneously with the releasing of the feed-roll mechanism to disengage the right-hand margin-stop from its 25 fixed adjustable position, so that it may be shifted back to a lower scale-position during the succeeding return movement of the carriage. This improved device may consist in providing an inner extension 29 on shaft 26, 30 the free end of which has a stud 30 to which a crank-arm 31 is rigidly mounted. A forwardly-extending link 32 may connect the crank-arm 31 to a swingable cam-plate-supporting-frame 33. Frame 33 may have left 35 and right, upstanding, forwardly-projecting members 37 and 38, which may be pivoted at 35 and 36, respectively, on depending supports 34. The supports 34 may be mounted on the carriage in any suitable manner, as 40 by means of screws 39. A cam-plate 40 may be rigidly fastened to the forwardly-projecting ends of members 37 and 38. The forwardly-projecting portion of member 37 may be offset to the left so as not to interfere with the grasping of the upstanding, 45 rigid finger 41, in the usual manner, when it is desired to return the carriage by means thereof.

The cam-plate 40 may have a front downwardly-sloping face 40^a which may bear 50 against the upper end of an upstanding, backwardly-extending pawl-finger 42. The finger 42 may form a part of a pawl-member 43 of a right-hand margin-stop 44. The 55 pawl-member 43 is pivotally supported, in the usual manner, by a shouldered screw 45, and may have a forwardly-projecting handle 46 at its lower end. A grip piece 47 may be rigidly fastened to the margin-stop 44, 60 which, together with the handle 46, may form means for pivotally swinging the pawl-member 43 on screw 45 to disengage teeth 48 on the pawl-member 43 from a stationary, carriage-supporting, rack-rod 49, to release 65 the margin-stop 44 and facilitate the move-

ment thereof. The rack-rod 49 has inclined teeth to allow the similarly-shaped engaging teeth 48 on the pawl-member 43 to easily ride over the rack-rod 49 to the left, or higher scale-position, but will act to positively stop movement to the right, or lower scale-position. The margin-stop 44 may be slidingly mounted on a margin-stop rod 50, and may be limited to movements between 70 adjustable collars 51 and 52 embracing rod 75 50. The collar 52 may have a supporting extension-piece 53, to which one end of a spring 54 is anchored. The other end of spring 54 may be fastened to the margin-stop 44 on a projecting lug 55. 80

The margin-stop 44 has extending inwardly thereon the usual stop-plate 63, which is arranged to extend into the path of a downwardly-projecting stop-lug 64 fastened to the middle of the front side of the carriage frame 10. 85

The carriage 10 is mounted to slide in the well-known manner on the carriage-supporting rack-rod 49 at the front of the platen 12 and on supporting rod 56 at the rear of the same. The usual letter-space indicating means may be provided, consisting of a scale 57, which is immovably mounted with its supporting bar 58 on the machine in front of the platen-carriage 10, and a pointer 59 which is mounted on the carriage 10 to move across the scale 57. The line-spacing mechanism 60 may be mounted on the left-hand corner of the platen-frame carriage 10 for use in the usual line-spacing and carriage-return movements. 95

There are several methods of operating a typewriter equipment with my improved device to automatically shift the right-hand margin-stop 44 back to a lower scale-position, but in all cases it is necessary to hold the feed-roll release or control lever 28 depressed during the return movement of the carriage. The preferable method is as follows: Let it be assumed that the typist has just finished typing work-sheet 12^a, which has the first entry 61 and column-items 62 typed beneath the same to the right thereof, and that the margin-stop 44 is up against collar 52 which gages the carriage 10 to the item-column position, as shown in Figure 1. The work-sheet 12^a is now ready to be replaced by another similar work-sheet requiring a first entry 61 thereon. Before the carriage 10 is given a return movement, the feed-roll release or control lever 28 is depressed in the usual manner, which causes the feed-rolls 17 to be thrown so as to release the work-sheet 12^a from the platen 12, and the work-sheet 12^a may be removed 110 from the machine. Depressing the feed-roll release or control lever 28 also rocks crank-arm 31, which moves link 32 to swing frame 33 so as to push the cam-plate 40 against the upstanding pawl-finger 42. It should be 115 120 125 130

noted that crank-arm 31 may be arranged to rock into an aligned position with the link 32 to assist in locking the control-lever 28 in depressed position, as shown in Figure 3. The finger 42 causes the margin-stop pawl 43 to swing on pivot-screw 45, so that the pawl-teeth 48 are disengaged from rack-rod 49. By pressing to the right the lever of the line-space mechanism 60 or the up-standing rigid finger 41, the carriage 10 is now given a return movement, and at the same time the margin-stop 44 is shifted to a lower scale-position corresponding to the first entry. The automatic return of margin-stop 44 takes place when the projecting lug 64, on the carriage 10, has been moved back sufficiently to strike the margin-stop plate 63 and thereafter slide the margin-stop 44 back with the carriage-return movement until the latter reaches the limiting collar 51. The collar 51 is adjusted to position the carriage for the first entry 61. The feed-roll release-lever 28, which is still in its depressed condition, holds the cam-plate 40 to displace the pawl-finger 42, so that the margin-stop pawl 43 is kept out of engagement with the rack-rod 49 during the return movement of the carriage. A new work-sheet 12^a may now be inserted and gaged between the platen 12 and the displaced feed-rolls 17, and the feed-roll release-lever 28 lifted to throw the feed-rolls 17 against the work-sheet 12^a and the platen 12 in the usual manner, as shown in Figure 2. The new work-sheet 12^a is now in proper position for typing the first entry thereon. The lifting of the feed-roll release-lever 28 also releases the margin-stop pawl 43 to engage the rack-rod 49.

As the carriage moves to the left after the first entry has been typed, the spring 54 automatically pulls along the margin-stop 44 from the lower scale-position until the limit-stop-collar 52 is reached, which marks the item-column position. There the margin-stop 44 is held against movement to the right by the margin-stop pawl 43. Since the feed-roll-release mechanism is left undisturbed during the typing operation, the return movements of the carriage 10 after the first entry has been made will be limited to the position of the item-column. Typing in the item-column may be continued until the work-sheet 12^a is finished, and the entire operation repeated on each new work-sheet. Thus, tabulation from the first-entry column to the item-column is eliminated by automatically shifting the margin-stop with the succeeding carriage return, and the margin-stop is automatically reset from the first-entry position to the item-column position.

Variations may be resorted to within the scope of the invention, and portions of the improvements may be used without others.

Having thus described my invention, I claim:

1. In combination with a typewriting machine having a letter-feeding carriage, releasably-adjustable means capable of either positioning the carriage on a lower scale-position for typing near the left-hand edge of a work-sheet or at a higher scale-position for typing to the right of the first-mentioned position, and means to simultaneously release the work-sheet and the positioning means when the latter is set at the higher scale-position, so that it may be automatically shifted with the carriage on its succeeding return movement to the lower scale-position.

2. In combination with a typewriting machine having a letter-feeding carriage, releasably-adjustable means capable of either positioning the carriage on a lower scale-position for typing near the left-hand edge of a work-sheet or at a higher scale-position for typing to the right of the first-mentioned position, means to simultaneously release the work-sheet and the positioning means when the latter is set at the higher scale-position, so that it may be automatically shifted with the carriage on its succeeding return movement to the lower scale-position, and means attached to the positioning means to automatically reset the same to the higher scale-position after being shifted therefrom.

3. In combination, in a typewriting machine having a carriage, means capable of either positioning the carriage on a lower scale-position for typing near the left-hand edge of a work-sheet or on a higher scale-position for typing to the right of the first-mentioned position, and means mounted on the carriage to release the positioning means when the same is set at the higher scale-position, so that it may be automatically shifted with the carriage on its succeeding return movement to the lower scale-position.

4. In a typewriting machine having a carriage, the combination of means capable of either positioning the carriage on a lower scale-position for typing near the left-hand edge of a work-sheet or on a higher scale-position for typing to the right of the first-mentioned position, means mounted on the carriage to release the positioning means when the same is set at the higher scale-position, so that it may be automatically shifted with the carriage on its succeeding return movement to the lower scale-position, and means acting on the positioning means to automatically reset the same to the higher scale-position after being shifted to the lower scale-position.

5. In a typewriting machine having a carriage, the combination of adjustable means capable of either positioning the carriage on a lower scale-position for typing near

the left-hand edge of a work-sheet or at a higher scale-position for typing to the right of the first-mentioned position, and means attached to the positioning means to automatically shift the same in the direction of carriage movement back to the higher scale-position after being displaced therefrom.

6. In a typewriting machine having a carriage, the combination of a margin-stop rod 10 mounted on a relatively stationary part of the machine, a margin-stop having a pawl forming part thereof, shiftably mounted on said rod to position the carriage in its return movement, adjustable collars on said 15 rod to gage and limit the margin-stop positions, a rack-rod mounted parallel to the margin-stop rod arranged to be engaged by said pawl to adjustably set the margin-stop, and means on the carriage for disengaging 20 said pawl from the rack-rod, so that the margin-stop will be released to shift from an adjusted position on the return movement of the carriage.

7. In a typewriting machine having a carriage, the combination of a margin-stop rod 25 mounted on a relatively stationary part of the machine, a margin-stop having a pawl forming part thereof shiftably mounted on said rod to position the carriage in its return movement, adjustable collars on said 30 rod to gage and limit the margin-stop positions, a rack-rod mounted parallel to the margin-stop rod arranged to be engaged by said pawl to adjustably set the margin-stop, a cam-plate mounted on and controlled 35 from the carriage to displace said pawl from engagement with the rack-rod, so that the margin-stop will be released to shift from an adjusted position on the return movement 40 of the carriage, and spring-means to automatically return the margin-stop to the adjusted position after being shifted therefrom.

8. In a typewriting machine having a carriage, the combination of a platen, feed-rolls 45 to hold a work-sheet thereto, a margin-stop rod mounted on a relatively stationary part of the machine, a margin-stop having a pawl forming part thereof shiftably mounted on said rod to position the carriage in its return movement, adjustable collars on said 50 rod to gage and limit the margin-stop positions, a rack-rod mounted parallel to the margin-stop rod arranged to be engaged by said pawl to adjustably set the margin-stop, and a control mounted on the carriage to 55 simultaneously throw the feed-rolls off the platen for releasing the work-sheet and disengage the pawl from the rack-rod, so that the margin-stop will be released to shift 60 from an adjusted position on the return movement of the carriage.

9. In a typewriting machine having a carriage, the combination of a platen, feed-rolls riding on the platen, a margin-stop

rod mounted on a relatively stationary part of the machine, a margin-stop having a pawl forming part thereof shiftably mounted on said rod to position the carriage in its return movement, adjustable collars on said 70 rod to gage and limit the margin-stop positions, a rack-rod mounted parallel to the margin-stop rod arranged to be engaged by said pawl to adjustably set the margin-stop, and a cam-plate having a control lever 75 mounted on the carriage for displacing said pawl from engagement with the rack-rod, so that the margin-stop will be released to shift from an adjusted position on the return movement of the carriage; said control 80 lever acting simultaneously to cause the cam-plate to displace the pawl and to throw the feed-rolls off the platen for releasing a work-sheet.

10. In a typewriting machine having a carriage on which a platen is mounted, the combination of feed-rolls riding on the platen to hold a work-sheet thereto, a margin-stop rod mounted on a relatively stationary 85 part of the machine, a margin-stop having a pawl forming part thereof shiftably mounted on said rod to position the carriage in its return movement, adjustable collars on said 90 rod to gage and limit the margin-stop positions, a rack-rod mounted parallel to the margin-stop rod arranged to be engaged by said pawl to adjustably set the margin-stop, a cam-plate having a control lever mounted on the carriage for displacing 95 said pawl from engagement with the rack-rod, so that the margin-stop will be released to shift from an adjusted position on the return movement of the carriage; said control lever acting simultaneously to cause the cam-plate to displace the pawl and to throw the feed-rolls off the platen for releasing 100 the work-sheet, and spring-means urging the margin-stop to automatically return to the adjusted position after being displaced therefrom.

11. In a typewriting machine having a carriage on which a platen is mounted, the combination of means for holding a work-sheet to the platen, a releasably-adjustable margin-stop to limit the return movement of the carriage, and a control to simultaneously release the holding means and the margin-stop from an adjusted position, so that the latter may be shifted with the carriage on its return movement.

12. In a typewriting machine having a carriage on which a platen is mounted, the combination of means for holding a work-sheet to the platen, a releasably-adjustable margin-stop to limit the return movement of the carriage, a control to simultaneously release the holding means and the margin-stop from an adjusted position, so that the latter may be shifted with the carriage on its return movement, and means acting on 125 130

- the margin-stop to reset the same to the adjusted position after being shifted therefrom.
13. In a typewriting machine having a platen-carriage, the combination of a releasably-adjustable margin-stop mounted on a relatively stationary part of the machine to position the carriage on its return movement, and means on the carriage to release the margin-stop from an adjusted position, so that it can be shifted with the return movement of the carriage.
14. In a typewriting machine having a carriage, the combination of a platen mounted on the carriage, feed-rolls riding on the platen to hold a work-sheet thereto, a releasably-adjustable margin-stop mounted on a relatively stationary part of the machine to position the carriage on its return movement, a control mounted on the carriage to throw the feed-rolls off the platen for releasing the work-sheet, and means to simultaneously release the margin-stop from an adjusted position, so that it can be shifted with the return movement of the carriage when the control acts to release the work-sheet.
15. In a typewriting machine having a carriage, the combination of a platen mounted on the carriage, feed-rolls riding on the platen to hold a work-sheet thereto, a releasably-adjustable margin-stop mounted on a relatively stationary part of the machine to position the carriage on its return movement, a control mounted on the carriage to throw the feed-rolls off the platen for releasing the work-sheet, means to simultaneously release the margin-stop from an adjusted position, so that it can be shifted with the return movement of the carriage when the control acts to release the work-sheet, and spring-means acting to automatically reset the margin-stop to the adjusted position after being shifted therefrom.
16. In a typewriting machine having a platen-carriage, the combination of a releasably adjustable margin-stop mounted on a relatively stationary part of the machine to position the carriage on its return movement, means on the carriage to release the margin-stop from an adjusted position, so that it can be shifted with the return movement of the carriage, and other means acting to reset the margin-stop to the adjusted position after being shifted therefrom.
17. In a typewriting machine having a platen-carriage, the combination of a releasably adjustable margin-stop mounted on a relatively stationary part of the machine to position the carriage on its return movement, and means on the carriage to shift the margin-stop from an adjusted position during the return movement thereof.
18. In a typewriting machine having a platen-carriage, the combination of a releasably adjustable margin-stop mounted on a relatively stationary part of the machine to position the carriage on its return movement, means on the carriage to shift the margin-stop from an adjusted position during the return movement thereof.
19. In a typewriting machine having a platen-carriage, the combination of a shiftably-adjustable margin-stop to position the carriage on its return movement, and means to automatically shift the margin-stop in the direction of carriage movement back to an adjusted position after being displaced therefrom.
20. In a typewriting machine having a letter-feeding carriage and a platen thereon, the combination of a margin-gage for the carriage, a rack for said margin-gage, and means for concomitantly releasing the work-sheet from the platen and releasing the margin-gage from the rack, the carriage moving said margin-gage idly along the rack.
21. In a typewriting machine having a letter-feeding carriage and a platen thereon, the combination of a margin-gage for the carriage, a rack for said margin-gage, means for concomitantly releasing the work-sheet from the platen and releasing the margin-gage from the rack, the carriage moving said margin-gage idly along the rack, and a stop finally arresting the carriage.
22. In a typewriting machine having a letter-feeding carriage and a platen thereon, the combination of a margin-gage for the carriage, a rack for said margin-gage, means for concomitantly releasing the work-sheet from the platen and releasing the margin-gage from the rack, the carriage moving said margin-gage idly along the rack, a stop finally arresting the carriage, and a returning spring connected to the margin-gage to move it when the carriage moves in opposite direction.
23. In a typewriting machine having a letter-feeding carriage and a platen thereon, the combination of a margin-gage for the carriage, a rack for said margin-gage, means for concomitantly releasing the work-sheet from the platen and releasing the margin-gage from the rack, the carriage moving said margin-gage idly along the rack, a stop finally arresting the carriage, a returning spring connected to the margin-gage to move it when the carriage moves in opposite direction, and a stop against which the spring returns said margin-gage.
24. In a typewriting machine having a letter-feeding carriage, the combination of a margin-gage for the carriage, a rack for said margin-gage, means upon said carriage for releasing said margin-gage from said rack, means also provided upon said carriage for

moving said margin-gage idly along said rack, and a spring connected to said margin-gage for returning it to normal position.

25. In a typewriting machine having a letter-feeding carriage, the combination of a margin-gage for the carriage, a rack for said margin-gage, means upon said carriage for releasing said margin-gage from said rack, means also provided upon said carriage for moving said margin-gage idly along said rack, a spring connected to said margin-gage for returning it to normal position, and adjustable collars or stops limiting the play of said margin-gage and the return movement of the carriage.

26. In a typewriting machine having a letter-feeding carriage, the combination of a returning device for said carriage, a margin-gage for the returning carriage, a rack for holding said margin-gage, means for releasing the margin-gage from the rack, the carriage in its return movement moving said margin-gage idly along the rack, and a stop finally arresting the carriage.

27. In a typewriting machine having a letter-feeding carriage, the combination of a returning device for said carriage, a margin-gage for the returning carriage, a rack for holding said margin-gage, means for releasing the margin-gage from the rack, the carriage in its return movement moving said margin-gage idly along the rack, a stop finally arresting the carriage, a spring returning the margin-gage along the rack, and a stop against which the spring returns said margin-gage.

28. In a typewriting machine having a letter-feeding carriage and a platen thereon, the combination of a margin-gage for the carriage, a rack for said margin-gage, and a bar mounted upon said carriage and extending lengthwise of the platen and movable laterally to release said margin-gage from said rack at different positions in the travel of the carriage and to maintain such release during travel of the carriage.

29. In a typewriting machine having a

letter-feeding carriage and a platen thereon, the combination of a margin-gage for the carriage, a rack for said margin-gage, a bar mounted upon said carriage and extending lengthwise of the platen and movable laterally to release said margin-gage from said rack at different positions in the travel of the carriage and to maintain such release during travel of the carriage, and a stop to limit the idle throw of the margin-gage effected by the carriage when said gage is released by said bar.

30. In a typewriting machine having a letter-feeding carriage and a platen thereon, the combination of a margin-gage for the carriage, a rack for said margin-gage, a bar mounted upon said carriage and extending lengthwise of the platen and movable laterally to release said margin-gage from said rack at different positions in the travel of the carriage and to maintain such release during travel of the carriage, a stop to limit the idle throw of the margin-gage effected by the carriage when said gage is released by said bar, and a stop to limit the return movement of the margin-gage.

31. The combination of a carriage, a margin-gage, a rack therefor, a dog engaging said rack, means for releasing the margin-gage from the rack and for holding it released while the gage is moved idly along the rack by the carriage, and stops limiting the extent of movement of the margin-gage which is effected by the carriage.

32. The combination of a carriage, a margin-gage, a rack therefor, a dog engaging said rack, means for releasing the margin-gage from the rack and for holding it released while the gage is moved idly along the rack by the carriage, stops limiting the extent of movement of the margin-gage which is effected by the carriage, and a spring returning the margin-gage at the movement of the carriage in the opposite direction.

JESSE A. B. SMITH.
